By Higdon Morgan ATTYS

UNITED STATES PATENT OFFICE.

JOHN O. ST. JOHN, OF ST. LOUIS, MISSOURI.

FIRE-CLAY BUILDING-BLOCK.

942,850.

Specification of Letters Patent. Patented Dec. 7, 1909.

Application filed August 31, 1907. Serial No. 380,884.

To all whom it may concern:

Be it known that I, JOHN O. ST. JOHN, a citizen of the United States, and resident of St. Louis, Missouri, have invented certain new and useful Improvements in Fire-Clay Building-Blocks, of which the following is a specification containing a full, clear, and exact description, reference being had to the accompanying drawings, forming a part 10 hereof.

My invention relates to improvements in fire clay building blocks, and the object of my invention is to construct a fireproof building block to be used in fireproof constructions, and to provide the same with means by which the running boards, base boards, picture molding, or any other finishing material may be fastened to the wall in which said blocks are used; and also affording a means by which the blocks may be held in proper alignment.

To the above purposes, my invention consists in certain novel features of construction and arrangement of parts, which will be 25 hereinafter more fully set forth, pointed out in the claims, and illustrated in the accompanying drawings, in which:—

Figure 1 is a portion of a wall, parts thereof being broken away, wherein my improved fireproof tiling or block is used; Fig. 2 is a perspective view of my improved fireproof tiling, or building block; Fig. 3 is a transverse section taken on the line 3—3 of Fig. 1; Fig. 4 is a section taken on the line 35 4—4 of Fig. 1.

Referring by numerals to the accompanying drawings:—1 designates my improved fireproof tiling, and formed in the face thereof is a dove-tailed groove 2. Located in 40 said groove 2 is a wooden block 3, which projects beyond the face of the tiling, corresponding to the thickness of the plastering.

The dove-tailed groove 2 is formed in the tiling in the process of its manufacture in 45 any suitable manner, and the wooden blocks 3 are cut to fit in said groove, preferably so that they may be moved therein. These fireproof tiling blocks are placed in the wall wherever it is desired to nail the finishing 50 material, such as the base board, running board, corner strips, or picture molding; and nails may be readily driven into the wooden strips 3.

Heretofore, in applying finishing material 55 to fireproof partitions made out of fireproof

tiling, it has been necessary to drive wedges into the joints of the tiling, which process is liable to dislocate the tiling located in the wall. By constructing a fireproof tiling as herein described, the wooden block 3 answers as suitable ground for applying the finishing material to the wall, and this block may be passed across the joints between two tilings, as illustrated in Fig. 1, which will hold the tiling in proper alignment. 65

A fireproof tiling block of my improved construction can be manufactured for about the same as the ordinary fireproof tiling, and by its use in fireproof construction, a substantial and convenient ground is afforded for the finishing material, and it also assists in holding the tiling in proper alignment. 70

The construction herein described is applicable for fire brick, or any block of hardened plastic material other than tiling. 75

I claim:—

1. The combination of two fire proof hollow building blocks provided with straight and parallel ends, sides and faces, each 80 block being formed of hardened plastic material and provided on one of its faces with a longitudinally disposed dove-tailed groove, the grooves in each block coinciding, a slideable wooden strip having dovetailed 85 side edges movably seated in the groove in each tile, answering the purpose of a nail block and also as a fastening means for holding said tiles in alignment, said wooden strip being greater in thickness than the 90 depth of the groove in the blocks.

2. As a new article of manufacture, a fireproof building block formed of hardened plastic material, the said building block being provided with parallel chambers, one of 95 which chambers is smaller than the other chambers, a longitudinal dove-tailed groove formed in one wall of the smaller chamber, the surfaces of said groove being smooth, and a wooden strip having dovetailed side 100 edges and of greater thickness than the depth of the groove in which it is located, said strip being free to move in said groove.

In testimony whereof, I have signed my name to this specification, in presence of two 105 subscribing witnesses.

JOHN O. ST. JOHN.

Witnesses:

E. E. LONGAN,
E. L. WALLACE.
